ATTORNEY

UNITED STATES PATENT OFFICE.

ROBERT LEMMER, OF MINNEAPOLIS, MINNESOTA.

MAIL DELIVERY AND RECEIVING DEVICE.

1,362,806.

Specification of Letters Patent. Patented Dec. 21, 1920.

Application filed September 15, 1919. Serial No. 323,967.

To all whom it may concern:

Be it known that I, ROBERT LEMMER, a citizen of the United States, and a resident of Minneapolis, in the county of Hennepin and State of Minnesota, have invented certain new and useful Improvements in Mail Delivery and Receiving Devices, of which the following is a specification.

The general object of this invention is to 10 provide an improved form of mail delivery device whereby mail may be delivered safely and economically from fast moving trains, and deposited in a suitable receptacle provided for the purpose.

15 One object of my device is to provide mechanism carried by the mail car that can be readily swung from an operative position on the exterior of the car to an inoperative and locked position on the interior of the car.

Another object is to provide in the car an 20 improved type of mechanism for safely holding a mail sack in the device until the actual point of delivery is reached, and at the same time will readily deliver the mail sack 25 when called upon to do so.

Another object is to provide a mail receiving mechanism having therein means for tripping the car delivery device, having also 30 means for taking up the shock of the delivery and having means for receiving the delivered mail into a suitable mail receptacle.

With these and incidental objects in view, the invention consists of certain novel features of construction and combination of parts, the essential elements of which are hereinafter described with reference to the drawings which accompany and form a part of this specification.

40 In the drawing, Figure 1 is a plan view of a portion of a car wall showing the delivery device mounted thereon, and showing the delivery device in dotted lines in two positions in the interior of the car; Fig.

45 2 is a front view of the mail delivery device as seen from the interior of the car; Fig. 3 is a side elevation of the delivery barrel; Fig. 4 is an end view of the same; Fig. 5 is a section taken on the line 5—5, Fig. 6; and Fig. 6 is a plan view of the mail receiving device.

Mounted on the wall 1, Fig. 1, of the car is a bracket 2 having a turn table 3 mounted

thereon. Hinged to the turn table at 4 is an arm 5 carrying a barrel 6.

By swinging the arm 5 in a clockwise direction, as shown in Fig. 1, the barrel 6 will swing in through the car door at 7, to the position shown dotted at 8.

By swinging the arm 5 upwardly about its hinged point 4 the barrel 6 may be 60 brought to the position shown dotted at 9, which is its normal riding position.

Lugs 10 on the turn table 3 serve to steady the arm 5 when it is riding in its outer or delivery position.

65 Mounted at 11, Fig. 3, is a bell crank one end 12 of which serves as a trigger, and the other end 13 of which is hinged at 14 to the link 15, which has its other end hinged at 16 to the link 17, hinged at 18 and carrying 70 the closure 19.

The mail sack that is to be delivered is placed in the barrel 6 while it is inside of the car, and the delivery device is then 75 swung to the outside of the car to the position shown in full lines in Fig. 1, and it will be apparent that neither wind pressure nor jolts received from the mail sack on the closure 19 can open that closure, because of the relative position of the hinged points 80 11, 14, and 16, but that if the trigger 12 is rotated in a counter clockwise direction, closure 19 will be opened so as to allow the mail sack to be readily delivered through that end of the barrel 6.

85 A slot 20 runs longitudinally of the barrel 6 to allow the easy passage therethrough of means provided in the receiving mechanism for working the trigger 12 and removing the mail sack from the barrel 6.

90 Looking now at the mail receiving mechanism, shown in Figs. 5 and 6, it will be seen that this comprises essentially a receptacle 21 having hinged to the walls 22 at 23 a tiltable frame 24 carrying at one end a 95 bumper 25.

Slidably mounted with respect to the receptacle 21 is a shaft 26 and a spring 27; and a set collar 28 normally holds this shaft in a position extending toward the right. A 100 head 29 is provided on one end of the shaft, which may strike the fixed collar 30 at the extreme left hand position of the shaft so as to limit the possible motion of the shaft.

Hinged at 31 on the lug 32, carried by the 105

shaft 26, is a link 33, the other end of which is hinged at 34 to one arm 35, of a bell crank hinged at 36, the other end of the bell crank 37 normally holding the end 38 of the frame 5 24, which by gravity or other suitable means is adapted to rest against the end 37 of the bell crank.

Hinged at 39 in the receptacle walls is a trap door 40, which by the counterweight 41 10 is normally held in a closed position against the stops 42, carried by the walls of the receptacle.

Suitably mounted on shaft 26 is a delivery disk 43 of such size as to freely pass 15 through the barrel 6 with suitable allowances made for inequalities of roadbed and swinging or rolling of the delivering car.

The support 44 carrying the disk 43 is sufficiently narrow to readily pass through 20 the slot 20 of the barrel 6 under the same operating conditions.

Hence it will be readily understood that if the receiving mechanism is suitably mounted at the side of the track the disk 43 will 25 sweep through the barrel 6, driving in front of it the mail sack carried therein, as the disk will first strike the trigger 12 and open the closure 19, before it can strike the mail sack itself and the mail sack will be 30 swept out of the barrel 6 before the closure 19 would have time to resume its closed position through its own weight.

The spring 27 takes up the jolt of the impact against the mail sack and, after the sack 35 has lost its momentum and the train has passed, throws the sack to the right.

When the disk 43 was moved to the left by the impact of the mail sack, the link 33 and bell crank swung the end 38 of the frame 40 24 downwardly, thereby lifting the bumper 25 against which the mail sack is thrown by the return of the disk 43.

The mail sack falls on the trap door 40 and its weight overcoming the balance of the 45 counterweight 41, the mail sack drops below the trap door through the framework 24 and falls on the bottom of the receptacle from where it is taken by the mail clerks.

While I have described my invention and 50 illustrated it in one particular design, I do not wish it understood that I limit myself to this construction, as it is evident that the application of the invention may be varied in many ways within the scope of the following claims:

1. In a mail delivery device, the combination of a bracket adapted to be mounted on the wall of a mail car and adjacent to the door thereof, a turn table mounted on said bracket, an arm hinged to said turn table, a delivery barrel carried by said arm, a closure for one end of said barrel, and means operable from the exterior of said car for open-

ing said closure so mail may be delivered from the closure end of said barrel. 65

2. In a mail delivery device the combination with a turn table of an arm hinged thereto, a delivery barrel carried by said arm and having both ends thereof open, a closure hinged to one end of said barrel and 70 adapted to close said end, said barrel having a longitudinal slot throughout the wall thereof.

3. In a mail receiving device the combination of a receptacle, a delivery disk slidably mounted with respect to said receptacle, a spring cushion for taking up impacts delivered against said disk, a bumper mounted to be swung into a receiving position in front of said delivery disk by the movement of said disk, under impact received thereby, whereby an object striking said disk may be thrown by said disk against said bumper. 75 80

4. In a mail receiving device the combination with a receptacle of a shaft slidably mounted thereon, a delivery disk carried by said shaft, a spring cushion associated with said shaft to take up impacts delivered against said delivery disk, a swingable bumper actuated by slidable movement of 85 said shaft, and a hinged trap door positioned in front of said bumper and adapted to receive thereon an object thrown from said disk and allow said object to pass by said trap door into that portion of the receptacle 90 95 below said trap door.

5. In a mail delivery and receiving device the combination of a delivery device comprising a delivery barrel having free passageway therethrough, but having a hinged 100 closure mounted at one end thereof, means for locking said closure in its closed position, means positioned in the opposite end of said barrel for opening said closure, and a receiving device comprising in combination a 105 receptacle, a delivery disk for actuating said closure opening means and sweeping mail matter positioned in said barrel therefrom.

6. In a mail delivery and receiving device the combination of a delivery device comprising a delivery barrel having free passageway therethrough, but having a hinged closure mounted at one end thereof, means for locking said closure in its closed position, means positioned in the opposite end 115 of said barrel for opening said closure, and a receiving device comprising in combination a receptacle, a delivery disk for actuating said closure opening means and sweeping mail matter positioned in said barrel 120 therefrom, and means including a trap door for receiving mail from said delivery disk past said trap door and to a receptacle positioned below.

ROBERT LEMMER.
